UNITED STATES PATENT OFFICE

2,507,855

COMBINED PACK FRAME AND TRUCK

Glen M. Drew, Kansas City, Mo.

Application July 22, 1946, Serial No. 685,304

1 Claim. (Cl. 280—63)

1

This invention relates to pack handling equipment and has for its primary aim the provision of a frame for packs, portions whereof may be brought into play when the pack is to be transported upon the wheels of the frame.

One of the important aims of this invention is the provision of a combined pack frame and truck, having means for holding a pack in position whether the same is to be carried on the back of a person or combined with a staff, gun or other "tongue" forming instrumentality whereby the pack and its frame may be drawn over the road in the same manner as would a small wheeled vehicle.

Other objects of the invention are to provide a pack frame of the aforementioned character, the form whereof is such as to effectively hold the pack in place against accidental engagement with the wheels forming a part of the assembly; to provide means on the frame for operably engaging a staff when the same is to be employed as a tongue or means for manually manipulating the frame and its supported pack; to provide parts on the frame for securing the pack in place; and to provide specially formed bearings or brackets on the frame for cooperating with a pair of staffs when the said frame is to serve as an ambulance or wheeled litter.

A large number of additional objects of the invention will appear during the course of the following specification, referring to the accompanying drawing, wherein:

Fig. 1 is a top plan view of a combined pack frame and truck made pursuant to the present invention and illustrating the manner in which a conventional pack may be carried thereby.

Fig. 2 is a sectional view taken on line II—II of Fig. 1.

Fig. 3 is a front elevational view of the frame with the wheels removed therefrom.

Fig. 4 is a fragmentary top plan view of the frame showing the manner in which the parts thereof are employed when the frame is to constitute a part of an ambulance or wheeled litter; and

Fig. 5 is a fragmentary detailed sectional view taken on line V—V of Fig. 4.

The form of the invention chosen for illustration has been developed particularly for use in handling back packs normally employed by military personnel and by Boy Scouts. Such packs are normally carried on the back by passing straps over the shoulders and beneath the arms but in many instances, the packs become injuriously burdensome due to their weight. It

2

is, therefore, desirable to have available some form of vehicle whereupon the pack may be mounted and drawn manually over the road when the pack is not worn on the back.

Since the frame of the device about to be described does not include a "tongue" or other means by which the pack and frame may be drawn over the road by the user, that instrumentality is provided by employing the staff which the Boy Scout normally uses and the rifle with which the military personnel is usually equipped.

The frame per se is light for it is constructed of tubular material and because of its light character does not add appreciably to the load when the pack is carried on the back. In the instance illustrated, the frame is broadly designated by the numeral 10 and comprises a substantially U-shaped body, the bight 12 whereof is arcuate in form while the legs 14 of the body are looped as at 16 to present a laterally disposed element adjacent to each of two wheels 18 that are mounted upon an axle 20. This axle bridges the distance between legs 14 of body 10 and has bearings 22 thereon to serve as connectors between the free ends of legs 14 of body 10 and the said axle 20. These bearings play an important part in converting the frame to uses other than pack carrying and are formed to present an annular groove 24 to the inside of each of the adjacent legs 14.

Loop 16 is contoured to serve as a guard against any accidental contact between wheels 18 and a pack 26 which is illustrated only by dotted lines in Fig. 1 of the drawing. When the pack 26 is mounted on the body 10 of the frame, it is to one side of the U-shaped frame and axle and is there held by a two part strap or similar element 28, each end whereof is secured to the uppermost portion of loops 16. The buckle 30 serves to allow strap 28 to be tightened against pack 26 and to removably hold the same in place. When the pack 26 is in the position normally assumed, it will extend above the peripheries of wheels 18 and the straps or shoulder elements on pack 26 may be drawn over the upper arms and back of the wearer without the wheels coming into engagement with any part of the person. When normally carried therefore, the wheels project outwardly from the back of the pack and the frame or body 10 is hung thereon.

In the event the pack is to be pulled along the road and wheels 18 are to be used as supporting elements for the entire assembly including pack 26, a tongue 32 is introduced in a manner illustrated in Figs. 1 and 2. In the instance shown,

tongue 32 is in the form of a staff having a hook 34 on one end thereof. This hook is received by a detent 36 on axle 20 when staff 32 is placed within a clip or fixture 38 carried by bight 12. A portion of staff 32 bridges the distance between bight 12 and axle 20 when a truck is to be formed and this part of the staff assists in supporting pack 26 along a zone thereof that would normally have a tendency to sag when wheels 18 were rolling upon a surface. A rifle or other similar instrument may be used in lieu of staff 32 when the nature of the equipment so dictates. When a rifle or like weapon is used in place of staff 32, it should be strapped on the top of the pack and the butt end of the same extended forwardly. 15 Under such conditions the rifle may be used by the soldier when lying in a prone condition.

When the frame is to be employed as a portion of an ambulance or wheeled litter, a pair of staffs 32 having hooks 34 at one end thereof are brought into play and the hooks are introduced into grooves 24 of bearings 22. This arrangement of parts precludes lateral displacement of the staff in each bearing groove 24 and as illustrated in Figs. 4 and 5, the staffs 32 will not move toward each other when a blanket is folded thereover. The outer ends of staffs 32 are left exposed beyond any blanket that may be folded thereover and the patient is slung between staffs 32 and in an inclined position with feet against axle 20, thus wheels 18 may be used as load bearing instrumentalities and one person can manipulate the ambulance or wheeled litter. 30

It is obvious from the foregoing that the pack frame may be readily converted from a back carried device to a miniature truck upon which the pack is mounted for movement along the road. It is also obvious that the pack may be carried without inconvenience due to the presence of the frame and that quick conversion to a truck type of pack frame may be made without removing the pack from its position upon the frame. 40

Many modifications and alterations may likewise be made without departing from the spirit of the invention or scope of the appended claim. 45

Having thus described my invention, what I

claim as new and desire to secure by Letters Patent is:

In a combined pack frame and truck, a normally horizontal axle having a wheel rotatably secured to each end respectively thereof; a U-shaped frame having the free ends of the legs thereof attached to said axle between said wheels, said legs each being formed adjacent the ends thereof to present a loop extending rearwardly, upwardly and thence forwardly from said axle in a vertical plane when the said free ends of said legs, said axle, and the bight of said frame are in a plane substantially parallel to the supporting surface; said loops extending upwardly a substantial distance for restraining lateral movement of the pack placed therebetween and carried on the frame, said loops serving as guards against any accidental contact between the wheels and the pack; a bearing on each of said free ends of the legs respectively for pivotally receiving said axle, said bearings each having an external groove formed therein circumscribing the axle; and a staff detachably engaging each bearing, each staff having a hook on one end thereof adapted for looping over a respective bearing within said groove thereof, said staffs extending from said axle in underlying supporting relationship to said frame.
